CLAIMThe ornamental design for a shoe upper, as shown and described.DESCRIPTIONFIG. 1 is a left side elevational view of a shoe upper showing my new design;

FIG. 2 is a right side elevational view thereof;

FIG. 3 is a top plan view thereof;
FIG. 4 is a front elevational view thereof; and
FIG. 5 is a rear elevational view thereof;
FIG. 6 is a left side elevational view of an alternate embodiment of my new design;
FIG. 7 is a right side elevational view thereof;

FIG. 8 is a top plan view thereof;
FIG. 9 is a front elevational view thereof; and,
FIG. 10 is a rear elevational view thereof.
The broken line showing of a shoe sole in the figures is environmental only and forms no part of the claimed design.

FIG. 1

FIG. 2

FIG. 3

FIG. 4

FIG. 5

FIG. 6

FIG. 7

FIG. 8

FIG. 9

FIG. 10
